UNITED STATES PATENT OFFICE.

ELBERT R. WINSLOW, OF GIBBON, NEBRASKA.

MOVING-PICTURE-MACHINE ATTACHMENT.

Application filed October 25, 1926. Serial No. 144,099.

The invention relates to a moving picture machine attachment.

The object of the present invention is to improve the construction of the picture machine attachment shown and described in application No. 129,818, filed by me August 17, 1926, more especially the switch mechanism for controlling the light circuit and the motor circuit of the moving picture machine and to provide a simple, practical, and exceedingly sensitive construction adapted to be readily operated by the breaking of the picture film and capable of simultaneously opening the light circuit and the machine circuit to extinguish the light and stop the machine.

A further object of the invention is to provide a device of this character which, when a film has been repaired or when a film is threaded through the machine, may be readily operated to close the breaks in the light circuit and the motor circuit, and which while being exceedingly sensitive and positively operative in the event of the breakage of a film, will at the same time permit a limited movement of a film engaging element to prevent operation of the mechanism when there is only a slight looseness or slack in the film.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a side elevation partly in section, of a moving picture attachment constructed in accordance with this invention.

Fig. 2 is a vertical transverse sectional view on the line 2-2 of Fig. 1, the vertically slidable plate being at the limit of its downward movement and the conductor bars thereof being out of contact with the upper and lower spaced terminals and the position of the film engaging arm of the rock shaft being illustrated in dotted lines.

Fig. 3 is a similar view showing the vertically slidable plate at the limit of its up-

ward movement for closing the light and motor circuits, the position of the film engaging arm of the rock shaft being illustrated in dotted lines.

Fig. 4 is a detailed view of the bottom brace of the attachment.

Fig. 5 is a detailed perspective view of one of the upper terminals.

Fig. 6 is a detailed view of one of the lower terminals.

In the accompanying drawings, in which is illustrated the preferred embodiment of the invention, the moving picture machine attachment comprises in its construction a base plate 1 consisting of an oblong piece of suitable material and adapted to be arranged upon a moving picture machine and to be secured to the same by a bolt 2 and a brace 3. The bolt passes through a suitable aperture 4 in the base plate 1 and through the supporting portion of the moving picture machine and is designed to have its lower portion arranged in a slot 5 of the brace 3. The brace is suitably secured to the lower face of the base 1 and is angularly bent between its ends to offset the slotted portion from the lower face of the base 1 to provide an intervening space between the base and the slotted portion of the brace for the reception of the supporting portion of the moving picture machine. Any other suitable means may of course be employed for securing the attachment to the moving picture machine.

The base is provided with spaced bearings 6 in which is journalled a horizontal rock shaft 7 provided at its front end with a curved upwardly extending arm 8 carrying a film-engaging roller 9. The roller 9 is mounted on a suitable journal 10 of the arm 8 and it is adapted to bear against the picture film for maintaining the arm and the rock shaft in a set position, and the roller rotates freely on the spindle so that the picture film passes over the roller. When the film breaks the curved arm and the roller swing downwardly and partially rotate the rock shaft and operate the switch mechanism hereinafter described for simultaneously opening the light circuit of the moving picture machine and the motor circuit thereof for shutting off the light and stopping the machine, and thereby effectually preventing any liability of the picture film becoming ignited by the lamp of the moving picture machine because of the breakage of the film and the

exposure of the film to the lamp. If desired, an adjustable coiled spring may be employed for coacting with the curved arm of the rock shaft to partially rotate the latter in the event of the breaking of the film, as shown and described in the said application.

The rock shaft 7 is equipped at its rear end with an arm 11 constituting a cam and having rounded faces at its outer end and operating within a cam housing 12 consisting of a piece of sheet metal secured by screws or other suitable fastening devices to a vertically slidable plate 13 and having its upper and lower portions bent at an angle to form horizontal flanges 14 and 15. The cam 11 operates between the upper and lower flanges 14 and 15 and is adapted when the rock shaft is partially rotated in one direction to engage the upper flange 14 and raise the slidable plate against the action of the coiled springs 16, and when swung in the opposite direction to engage the lower flange 15 for positively moving the slidable plate downwardly in conjunction with the action of the coiled spring 16. The upper and lower horizontal flanges 14 and 15 constitute the top and bottom walls of the cam housing and fit against the slidable plate 13 and space the vertical portion of the cam housing from the slidable plate to provide an intervening space for the cam 11. When the film is threaded through the moving picture machine the arm 8 is raised and carries the cam 11 into engagement with the upper flange or wall 14 of the housing and moves the slidable plate 13 upwardly, and when the film either breaks or is exhausted the arm 8 will swing downwardly and carry the cam 11 into engagement with the lower flange 15 and move the slidable plate downwardly. The coiled springs 16 are connected with the slidable plate and with a fixed base plate 1, and are adapted to move the slidable plate downwardly as soon as the slidable plate is released from the means hereinafter described.

The fixed supporting plate 17, which is constructed of fiber or other insulating material, is secured adjacent the lower edge to ears or flanges 18 of the base plate 1, but any suitable means may of course be employed for mounting the fixed supporting plate upon the base 1. The slidable non-conducting or insulating plate is provided at opposite sides of its intermediate portion with slots 19 through which pass screws 20 constituting binding posts for motor circuit wires 21. The screws 20 have smooth portions which are arranged in the slots 19, and reduced threaded portions which pass through the fixed supporting plate 17 and which are provided with nuts 22 for securing the wires of the motor circuit to the device. The reduced threaded portions form shoulders at the inner ends of the smooth portions which abut against the fixed supporting plate and pre-

vent the heads of the binding screws 20 from clamping the vertically slidable plate. This construction provides for a free sliding of the plate 13 in its upward and downward movement.

The sliding plate is provided at the lower ends of the slots with a transverse conductor bar 23 having a central attaching portion and upwardly diverging arms or terminal portions which engage the terminal binding screws and close the motor circuit when the plate 13 is at the limit of its upward movement. The terminal portions of the conductor bar 23 engage the heads of the terminal bolts or screws 20 and the sliding plate is also provided at its upper edge with a transverse conductor bar 24 consisting of a strip of suitable conducting material projecting upwardly beyond the slidable plate 13 and having its projecting portion 25 slightly bevelled and arranged to engage over or in front of a pair of upper terminals 26. The upper terminals 26, which are constructed of suitable conducting material, are approximately U-shaped and straddle the upper edge of the fixed supporting plate 17 and are secured to the same by screws 27 or other suitable fastening devices which form binding posts for the attachment of wires 28 of the light circuit. The front sides of the upper terminals 26 are slightly bevelled at 29 to enable the conductor bar to readily slide in front of or over the front sides of the upper terminals and form a tight electrical connection between the conductor bar 24 and the upper terminals. The upper conductor bar contacts with the upper terminal simultaneously with the closing of the motor circuit by the lower conductor bar, and the slidable plate 13 is adapted by its upward and downward movement to close and open these circuits simultaneously.

When the slidable plate 13 is moved upwardly by the cam it is held in such raised position by means of a setting catch 30 consisting of a lever provided intermediate of its ends with an eye 32 which is mounted on a suitable pivot 33 consisting of a screw bolt or similar fastening device. The slidable plate 13 is provided at the pivot 33 with an oblong opening 34 of sufficient size to permit the necessary vertical movement of the plate 13 without the same coming in contact with the pivot 33. Mounted on the pivot 33 is a spring plate or washer 35 which is adapted to press the plate 13 inwardly toward the fixed supporting plate 17 to create sufficient friction to maintain the upper conductor bar firmly in engagement with the upper terminals. The upper arm of the lever constituting the setting catch is reduced at the right hand side in Figures 2 and 3, to provide a shoulder 36 which is carried into engagement with a fixed catch 37 consisting of an approximately L-shaped piece secured to the

upper portion of the sliding plate 13. The pivoted setting lever or catch 30 is urged towards the fixed catch by a coiled spring 38 connected at one end to the lower arm of 5 the setting lever and at the other end to the plate 13, and it maintains the setting lever in engagement with the fixed catch 37. When the sliding plate 13 is raised by the cam the shoulder 36 is carried beneath the fixed catch 37, which is elevated to a point 10 above the shoulder by the vertical movement of the sliding plate 13. This will prevent the sliding plate from dropping back and will permit a limited play of the cam between the flanges without actuating the sliding plate.

In order to trip the setting catch slightly in advance of the engagement of the cam with the lower flange, the rock shaft 7 is 20 provided with an approximately L-shaped trip arm 39 located adjacent the cam and arranged to engage the lower arm of the setting lever and move the same against the action of the coiled spring 38 when 25 the rock shaft 7 is partially rotated by the arm 8 and the roller 9 through either the breaking of a film or the movement of the inner end of the film beyond the roller after a complete showing of the film in the motion 30 picture machine. The cam and the setting lever are arranged to permit a limited movement of the parts to prevent any loosening or slack in the film from operating the device. The lower end of the setting lever 30 35 is provided with a forwardly projecting pin 43 and the arm 39 is adapted to slide readily over the pin 43, and the arm 39 is of sufficient length to permit the necessary sliding movement without becoming disengaged from the lever, also the terminal portion 40 of the L-shaped arm forms a stop and will prevent disengagement of the arm and the setting lever.

The device is provided with a removable 45 outer casing 40 which fits over the switch mechanism and which is provided at opposite sides with depending spring catches 41 for engaging beneath the base plate at opposite sides thereof. The casing 40 is provided at the front with an opening 42 receiving the rock shaft and extending to the lower edge of the casing to permit the latter to be placed over and removed from the switch mechanism without contacting with 50 the rock shaft.

What I claim is:

1. A moving picture machine attachment comprising film controlled mechanism including a rock shaft having means to bear against a film and for rotating the rock shaft when the film engaging means is released by the film, switch mechanism having spaced upper and lower contacts arranged in pairs and adapted to be included in the circuits of the machine and the lamp thereof, a vertically movable plate provided with conductor bars adapted to be carried into and out of engagement with the said contacts, a cam carried by the rock shaft for actuating the sliding plate, a fixed catch carried by the vertically movable plate, a pivoted setting lever mounted independently of the sliding plate and arranged to engage with the fixed catch for supporting the sliding plate in an elevated position, and means carried by the rock shaft for engaging the setting lever to trip the sliding plate.
2. A moving picture machine attachment comprising film controlled mechanism including a rock shaft having means to bear against a film and for rotating the rock shaft when the film engaging means is released by the film, switch mechanism having spaced upper and lower contacts arranged in pairs and adapted to be included in the circuits of the machine and the lamp thereof, a vertically movable plate provided with conductor bars adapted to be carried into and out of engagement with the said contacts, a cam carried by the rock shaft for actuating the sliding plate, setting mechanism for holding the sliding plate in an elevated position, and a tripping device carried by the rock shaft for releasing the setting mechanism.
3. A moving picture machine attachment comprising film controlled mechanism including a rock shaft having means to bear against a film and for rotating the rock shaft when the film engaging means is released by the film, switch mechanism having spaced upper and lower contacts arranged in pairs and adapted to be included in the circuits of the machine and the lamp thereof, a vertically movable plate provided with conductor bars adapted to be carried into and out of engagement with the said contacts, a cam carried by the rock shaft for actuating the sliding plate, a fixed catch carried by the vertically movable plate, a pivoted setting lever mounted independently of the sliding plate and arranged to engage with the fixed catch for supporting the sliding plate in an elevated position, and means carried by the rock shaft for engaging the setting lever to trip the sliding plate.
4. A moving picture machine attachment comprising film controlled mechanism including a rock shaft having means to bear against a film and for rotating the rock shaft when the film engaging means is released by the film, switch mechanism having spaced upper and lower contacts arranged in pairs and adapted to be included in the circuits of the machine and the lamp thereof, a vertically movable plate provided with conductor bars adapted to be carried into and out of engagement with the said contacts, a cam carried by the rock shaft for actuating the sliding plate, a fixed catch carried by the vertically movable plate, a pivoted setting lever mounted independently of the sliding plate and arranged to engage with the fixed catch for supporting the sliding plate in an elevated position, and means carried by the rock shaft and arranged to engage the setting lever to move the latter out

of engagement with the fixed catch to trip the sliding plate.

5. A moving picture machine attachment comprising film controlled mechanism including a rock shaft having film contacting means, switch mechanism having spaced contacts adapted to be included in the circuits of the machine and the lamp thereof, a vertically slideable plate having conductor bars arranged to engage the said contacts to close the said circuits and adapted also to be carried out of engagement with the contacts by the downward movement of the sliding plate, a cam housing mounted on the sliding plate, and a cam carried by the rock shaft and operating in the housing and arranged to engage the same for actuating the sliding plate.

6. A moving picture machine attachment comprising film controlled mechanism including a rock shaft having means for engaging a film, switch mechanism having spaced contacts adapted to be included in the circuits of the machine and the lamp thereof, a vertically sliding plate provided with conductor bars coacting with the spaced contacts and movable out of and into engagement with the same to close and open the said circuits, coiled springs located at opposite sides of the sliding plate and connected with the same for urging the said plate downwardly, a cam carried by the rock shaft, and spaced means mounted on the sliding plate and located at opposite sides of the cam for coacting therewith, whereby the cam is adapted to move the sliding plate upwardly and downwardly.

7. A moving picture attachment comprising film controlled mechanism including a rock shaft having means for engaging a film, a fixed insulating plate, a vertically slideable insulating plate provided with slots, terminal bolts operating in the slots and securing the sliding plate to the fixed plate,

upper contacts mounted on the fixed plate, 45 conductor bars carried by the slideable plate and arranged to engage the terminal bolts and the upper contacts, and means carried by the rock shaft for raising and lowering the slideable plate.

8. A moving picture machine attachment comprising a film controlled mechanism including a rock shaft having a film engaging means, a fixed supporting plate of insulating material, a slideable plate of insulating material provided with slots, terminal bolts mounted on the fixed plate and operating in the slots of the slideable plate, approximately U-shaped contacts straddling the upper edge of the fixed plate, 60 a lower conductor bar mounted on the slideable plate and arranged to engage the terminal bolts, an upper conductor bar carried by the slideable plate at the upper end thereof and arranged to engage with the upper 65 contacts, and means carried by the rock shaft for raising and lowering the slideable plate.

9. A moving picture machine attachment comprising film controlled mechanism including a rock shaft and having means for engaging a film, a fixed supporting plate, spaced contacts mounted on the supporting plate at the top thereof, a slideable plate, a conductor bar carried by the slideable plate 75 and arranged to engage the said contacts, a pivoted setting lever having a pivot mounted on the supporting plate, a spring plate arranged on the pivot of the lever and engaging the slideable plate and maintaining 80 the conductor bar in tight engagement with the said contacts, means carried by the rock shaft for actuating the slideable plate, and a fixed catch mounted on the slideable plate and arranged to be engaged by the setting lever. 85

In testimony whereof I have hereunto set my hand.

ELBERT R. WINSLOW.
